PUNCH REMOVER

Newman M. Marsilius, Trumbull, Conn.

Application April 17, 1947, Serial No. 742,190

1 Claim. (Cl. 29—256)

1

This invention relates to new and useful improvements in shop equipment and has particular relation to a means for separating the punch holder and bed of a die set.

An object of the invention is to provide a simple yet effective means whereby the punch holder and bed of a die set may be separated with a minimum of effort.

Another object is to provide a die set separator having the characteristics stated and which is adapted for drawing the punch holder off the guide pins of the die set by a smooth straight line movement and which means is capable of exerting great effort for the purpose indicated with relatively slight exertion on the part of the operator.

Another object is to provide a die set separator adapted for use in separating the elements of various sizes of die sets and which may be secured to the shank of the punch holder or which may be secured to the punch holder independent of the shank of the latter.

Other objects and advantages of the invention will become apparent from a consideration of the following detailed description taken in connection with the accompanying drawings wherein satisfactory embodiments of the invention are shown. However, it is to be understood that the invention is not limited to the details disclosed but includes all such variations and modifications as fall within the spirit of the invention and the scope of the appended claims.

In the drawings:

Fig. 1 is a top plan view of a die set separator made in accordance with the invention;

Fig. 2 is a front elevational view thereof, the lower portions of the legs of the base being omitted;

Fig. 3 is a side elevational view of the device as shown in Fig. 2;

Fig. 4 is a view somewhat similar to Fig. 3 showing a modified construction of the means for attachment to the punch holder; and

Fig. 5 is a sectional view taken as along the line 5—5 of Fig. 4.

Referring in detail to the drawings, at 10 is generally indicated the base of the machine and the same includes legs and a supporting structure 11 on the upper side of which is secured, in any suitable manner, a top 12 including a table 13 providing a work support. This table 13 is provided with a multiplicity of tapped openings as at 14, which openings function in connection with clamping means for the clamping of various sizes and shapes of die set beds to the table, as will later appear.

2

On the rear of the top 12 is a split bracket 15 having a vertical opening therethrough and in which vertical opening is disposed the lower end of a vertical post or column 16 of substantial size so as to provide the desired rigidity. The portions of the split bracket are designed to be drawn together by a bolt construction 17 which passes through an ear 18 of the bracket and is threaded into a tapped opening through the ear 19 thereof.

Clearly, on tightening of the bolt 17, the ears 18 and 19 will be drawn toward one another clamping the split bracket about the received portion of the post or column 16. If desired, a set screw or other means 20 may be passed through a side of the bracket and engaged with the lower portion of the post or column to hold the same against any turning movement relative to the bracket and to the top 12. Extensions 21 integral with the bracket and top may provide pockets for the reception of small tools or the like.

Mounted on the post or column 16 for vertical movement therealong is a slide generally designated 22. This slide includes a body 23 encompassing the post 16 and carrying a key 24 held to the slide as by screws 25 and entering into a keyway 26 extending longitudinally of the post. Additionally, forwardly of the post, slide 22 has an opening or passage 27 extending vertically therethrough in parallel relation with the post. In the upper portion of said passage, an internally threaded nut or bushing 28 is located and the same is fastened to the body of the slide and against all turning movement relative to such body as by means of screws or the like 29.

A cap 30 is fastened on the upper end of the post as by screws or the like 31 and the same includes a portion 32 extending forwardly of the post and over the forward portion of the slide body 23. Through such forward portion 32 of the cap there extends the unthreaded portion 33 of a feed screw 34 threaded into the nut or bushing 28 above mentioned. The screw 34 is held against any longitudinal movement as by collars 35 and 36 disposed at the upper and lower sides of the cap portion 32 and secured to the screw as by dowels or the like 37. A crank or other means 38 is applied to the upper end of the screw for rotating the same.

With this construction, it will be clear that on manipulation of the crank 38 the screw 34 may be rotated and having threaded engagement with the nut or bushing 28 and the latter being rigid with the slide 22, such slide will be raised or lowered along the post 16 depending on the di-

rection in which the crank is turned. Owing to the presence of the collars 36, it will be clear that the screw 34 is not adapted for longitudinal movement but only for rotary movement. Owing to the presence of the key and keyway 24 and 26, the slide 22 is adapted only for movement along the column or post 16 and will have no tendency to turn about the latter and so there will be no undue tendency for binding of the slide with respect to the screw 34.

At its forward side, slide 22 includes an extension 39 through which is threaded a clamping screw 40 having a head 41 rotatably secured to its lower end. For this purpose, a pin 42 may secure the head and the lower portion of the screw shank together for movement of the head with the screw shank when the latter is moved vertically. However, as the head 41 is brought into engagement with the work, the screw shank may be rotated to further clamp the head against the work without imparting turning movement to the head.

In the forward face of its lower portion 43, the slide body 23 is provided with a groove 44 and at the upper and lower sides of said groove with flat faces 45 and 46. The groove 44 and the faces 45 and 46 are designed for the mounting of different constructions of parts for cooperation with different constructions or sizes of dies.

In Figs. 1-3, the part so mounted is generally designated 47 and the same is in the nature of a jaw designed to cooperate with the clamping screw 40. Such part 47 is somewhat L-shaped in transverse section or in side elevation and the same includes a rigid arm or jaw 48 shown as arranged horizontally and a second arm or jaw 49 arranged vertically.

This latter jaw is provided with a rib 50 adapted to be received in the groove 44 above described and with upper and lower flat faces at the upper and lower sides of said rib and designed to engage the flat faces 45 and 46 of the body 23. A suitable number of screws 51 passing through the arm 49 and into the body 23 at opposite sides of the passage 27 serve to secure the part 47 to the body 23 for movement therewith. On its upper surface, the jaw 48 of the part 47 may be provided with a wearplate 52.

When using the device of Figs. 1-3, the die set, the punch holder and bed of which is to be separated, is disposed on the upper side of the table 13 in at least approximately centered relation with the post or column 16. Then a pair of similar clamps 53 and 54 are positioned on studs 55 and 56 which are threaded into selected of the tapped holes 14. As shown in Fig. 1, these studs pass through slots 57 in the clamps whereby the clamps may be adjusted inwardly and outwardly on the studs within the limits provided by the lengths of the slots. Nuts 58 on the upper ends of the studs prevent movement of the clamps off the studs and they are preferably tightened down sufficient to cause the clamps to bear against the upper side of the die bed, as for example, the die bed 59.

Thus, it will be understood that the clamps actually extend over the die bed and under the punch holder as into the space normally separating such parts due to the presence of bushings 60. Thereafter, clamping screws 61 and 62, threaded through the outer end portions of the clamps 53 and 54, respectively, are tightened so as to raise upwardly on the outer ends of the clamps and thereby exert a downward force on the die bed 59 through the inner portions of the

clamps. As shown, the screws 61 and 62 have their lower ends disposed in buttons 63 which actually bear against the upper surface of the table 13. With the clamps 53 and 54 tightened, it will be appreciated that the entire die set is positioned since the punch holder 64 of the set is on such bed and on the guide pins 65 of the set.

At this time, the jaw-like portion 48 of the part 47 is also entered between the bed and the punch holder of the die set and the screw 40 is tightened to clamp a portion of the punch holder 64 against such jaw 48. When this has been successfully accomplished, the operator merely rotates the crank 38 moving the slide 22 upwardly on the column or post 16. As this is done there is a straight upward movement of the whole slide and the slide being clamped to the punch holder, the latter is shifted vertically along and removed from the guide pins 65.

Heretofore, punch holders and the beds of die sets have usually been separated with a great deal of physical effort. The tool maker pries and taps at the parts until he gets them separated. With my present means, they are easily separated with a minimum of effort and with my present means, the punch holder may be reapplied by lining up the bushed openings with the guide pins 65 and operating the crank in the reverse direction to lower the punch holder on the pins. In fact, in some instances, the machine may be used to test tools which have been applied to the parts of the die set.

Referring now to Figs. 4 and 5, the machine as there shown is essentially the machine previously described and the same parts have been given the same reference characters and will not be again described. The modification resides in the employment of a gripping device generally designated 66 for gripping the shank of the punch holder and this device 66 is substituted for the part 47 of Figs. 1-3.

Essentially, the gripper 66 comprises a generally L-shaped body including a rigid horizontal arm 67 and a vertical arm 68, the latter being provided on its rear face with a rib 69 and flat surfaces above and below said rib. Rib 69 is received in the groove 44 in the body 23 of the slide and the flats at opposite sides of the rib engage flats 45 and 46 of the slide. The screws 51 used for securing the part 47 to the slide may also be used for securing the part or gripper 66 to the slide.

In its forward face or edge, the arm 67 of the gripper is provided with an arcuate notch or recess 70 and a separate clamping element 71 is provided with a similar notch or recess 72. Clamping screws 73 pass through the part 71 and are threaded into the forward edge of the arm 67. When using the structure of the modification (see Figs. 4 and 5) the bed 74 of the die set is clamped to the upper surface of the table 13 as previously described and the die set is located to dispose the shank 75 of the punch holder 76 in alignment with the opening provided by the notches 70 and 72. Thereafter, the slide 22 is lowered until the shank 75 is located in the opening provided by the notches 70 and 72 and the screws 73 are tightened whereby the shank 75 of the punch holder is gripped, as illustrated in Fig. 4.

The operation of the modified structure is the same as that previously described and as the bed 74 is clamped in place and the shank gripping device 66 is clamped to the shank 75 of the punch holder, the crank 38 is operated to rotate the screw 34 to draw the punch holder upwardly off the guide pins 65 or lower it onto the guide pins

depending on the direction in which the crank is moved.

In the structure of the modification, the clamping screw 40 is not employed. However, the modification will serve to illustrate that my machine is adapted for the handling of different types of die sets in some of which the punch holder is not provided with the shank, the same as or equivalent to the shank 75 of the die set of Figs. 4 and 5. Thus, with my disclosed device, means are provided for clamping any construction of die bed to the machine base and any construction of punch holder to the slide 22. Where the shank is grasped, the punch holder is pulled upwardly and where the jaw 48 enters under the punch holder the latter is lifted.

Having thus set forth the nature of my invention, what I claim is:

In a die set separator, a base adapted to support a die set, means to secure the bed of a die set against the upper side of said base, a vertical post extending above said base, a slide on and movable along said post and extending inwardly therefrom over said base, said slide including an inwardly extending arm portion adapted to be disposed at the underside of the punch holder of a die set on said base, a screw clamp on said slide above said arm and adjustable vertically toward and from said arm and when adjusted toward the same adapted to engage the upper side of such a

punch holder whereby the latter is clamped between said jaw and screw clamp for upward and downward movement with said slide from and toward the bed of the die set, and a screw relatively mounted on the inward side of said vertical post, including manually operative means, secured to the upper end of said screw for rotation thereof, and a nut secured to said slide through which said screw is threaded, whereby said slide may be raised or lowered by rotation of said screw.

NEWMAN M. MARSILIUS.
